UNITED STATES PATENT OFFICE.

POMPEO GUADAGNINI, OF LONDON, ENGLAND.

SELF-LIGHTING CIGAR OR CIGARETTE.

SPECIFICATION forming part of Letters Patent No. 674,406, dated May 21, 1901.

Application filed March 23, 1900. Serial No. 9,921. (No model.)

To all whom it may concern:

Be it known that I, POMPEO GUADAGNINI, a citizen of Italy, residing at 10 Dacres road, Forest Hill, London, England, have invented 5 certain new and useful Improvements in Self-Lighting Cigars or Cigarettes; and I do hereby declare the following to be a full, clear, and exact description of the invention, such as will enable others skilled in the art to which it ap-

10 pertains to make and use the same.

My invention relates to the manufacture of cigars and cigarettes; and it consists in the combination, with a cigar or cigarette, of a device whereby the same may be lighted without the use of matches.

15 In the accompanying drawing the figure is an elevation of a cigar or cigarette provided with my lighting device.

In practicing my invention I prepare an adhesive substance—such, for instance, as used in so-called “wind” or “blazing” matches—which, when dry, possesses the quality of burning slowly and cannot be extinguished by a blast of wind, and a small head of some 25 substance ignitable by friction. These heads may be made of the same substance as applied to the heads of ordinary or of the so-called “safety-matches” and are affixed by means of a slowly-burning adhesive substance to a cigar 30 or cigarette *a* on or near the lighting-end thereof, as shown in the drawing. Next I prepare a cap (designated by letter *c* in the

drawing) having a frictional surface on its inside. This cap *c* is set upon the end of the cigar, so as to cover the head *d* and so that in 35 removing it the frictional surface provided on its inside rubs against the head *d*, thereby causing it to ignite. The burning of the head causes the substance *b*, by which the tip is applied to the cigar, to burn, and in this manner the cigar itself is lighted.

If the head *d* is made of such substance as used on the heads of so-called “safety-matches,” then the rubbing-surface on the inside of the cap must be prepared of such material as used for preparing the rubbing-surface on the boxes for safety-matches.

I claim as my invention—

A device for lighting cigars or cigarettes, consisting of a layer of slowly-burning adhesive substance, applied to the lighting end of a cigar or cigarette, a tip of a substance, ignitable by friction, set on the slowly-burning adhesive substance and of a cap, applied to the cigar so as to cover the ignitable substance and provided with a frictional surface causing the latter to ignite when the cap is removed.

In testimony whereof I affix my signature in presence of two witnesses.

POMPEO GUADAGNINI.
